POURING ATTACHMENT FOR CONTAINERS

Frank Massari, Tampa, Fla.

Application June 6, 1950, Serial No. 166,349

6 Claims. (Cl. 222—86)

1

This invention relates to new and useful improvements in pouring attachments for containers and relates to my copending application Serial No. 92,199, filed May 9, 1949, now Patent No. 2,558,575, dated June 26, 1951.

The primary object of the present invention is to provide a pouring attachment including a pouring spout having a cutter formed therewith that will punch out a small piece of metal in the upper wall of a container and which cutter is so constructed as to permit the piece of metal punched out to remain attached to the upper wall of the container.

Another important object of the present invention is to provide a pouring attachment of the aforementioned character wherein the pouring spout includes a downwardly tapered portion joined with the cutter so that as the cutter and the tapered portion are forced into the upper wall of a container the edges defining the opening so formed will yieldingly grip the spout to support the container relative to the attachment.

Yet another object of the present invention is to provide a pouring attachment for containers including a spout having a vertically inclined dispensing end that slopes downwardly toward the interior of a hollow body supporting the spout so that any liquid in the spout will drain toward the body when the body is supported in a substantially vertical position.

Another object of the present invention is to provide a pouring attachment for containers involving a novel and improved vent means for increasing the efficient pouring of liquid from a container housed within the attachment.

A further object of the present invention is the provision of a pouring attachment for containers involving a hollow body adapted to receive and retain a container therein and an insulating sleeve within the body for embracing a container so that the outer periphery of the case will not become cold under refrigeration and thereby preventing or restricting the formation of condensation on the outer periphery of the body.

A still further aim of the present invention is to provide a pouring attachment for containers that is simple and practical in construction, strong and reliable in use, small and compact in structure, neat and attractive in appearance, efficient and durable in operation, inexpensive to manufacture, and otherwise well adapted for the purposes for which the same is intended.

Other objects and advantages reside in the details of construction and operation as more

2

fully hereinafter described and claimed, reference being had to the accompanying drawings forming part hereof, wherein like numerals refer to like parts throughout, and in which:

5 Figure 1 is an elevational view of the present invention;

Figure 2 is a plan view of Figure 1;

Figure 3 is a vertical sectional view taken substantially on the plane of section line 3—3 of Figure 2;

10 Figure 4 is a horizontal sectional view taken substantially on the plane of section line 4—4 of Figure 3;

Figure 5 is a horizontal sectional view taken substantially on the plane of section line 5—5 of Figure 3;

15 Figure 6 is an enlarged detail vertical sectional view showing the pouring spout and the cutter formed therewith;

20 Figure 7 is a vertical sectional view taken substantially on the plane of section line 7—7 of Figure 6; and,

Figure 8 is a vertical sectional view of the present invention in slightly modified form.

25 Referring now to the drawings in detail, wherein for the purpose of illustration, there is disclosed a preferred embodiment of the present invention, the numeral 10 represents a hollow body or case of any suitable material, such as

30 plastic, stainless steel or the like, having an open bottom and an upper end wall 12. The body 10 may be cylindrical and is preferably formed with a plurality of flutes or hollow vertical ribs 14 that will aid in yieldingly gripping and holding a container or can 16 within the body.

35 The upper wall 12 is formed with a central recess 18 in its lower face in which there is mounted an arcuate vent tube 20 having a downwardly curved end extension 22 that extends through and which is frictionally fitted in a downwardly curved opening 24 in the end wall 12. The lower downwardly and inwardly tapered end 26 of the extension 22 terminates in a cutter 28 having a pair of diametrically opposed

40 V-slots 30 therein whose edges are inwardly beveled for penetrating the upper wall 32 of the can 16 as the body 10 is forced down upon the can or as the can is forced into the body.

45 The inward bevel of the edges defining the slots 30 will force the material of the wall 32 cut or punched by the cutter to bend downwardly but still remain attached to the wall 32. Furthermore, the tapered end 26 will expand the edges defining the opening made by the cutter

3

28 whereby the edges will yieldingly grip the extension 22 to aid in supporting the container within the body 10.

The upper wall 12 is formed with an additional central recess 34 in its upper face that slidably receives a finger grip 36 at the upper end of an ejecting shank 38. A pressure plate 40 is supported at the lower end of the shank 38. The wall 12 is provided with a reinforced axial bore 42 that slidably receives the shank 38. As the finger grip 36 is forced into the recess 34, the pressure plate 40 will engage the upper wall 32 of the container to force the container from the open bottom of the body 10.

The inner surface of the body 10 is coated with an insulating material or receives an insulating sleeve 44 that will tend to prevent the formation of condensation on the outer surface of the body and thereby permit handling of the device in a convenient manner.

A substantially V-shaped tubular spout 46 is supported by the body 10 and more specifically by the end wall 12. This spout comprises an upwardly and outwardly inclined leg portion or dispensing end 48 that extends outwardly through and which is frictionally fitted in an upwardly and outwardly inclined opening 50 in the end wall 12. The vertical leg portion 52 of the spout 46 is located within the body 10 and includes a downwardly extending, inwardly tapered end portion or shoulder 54 that terminates in a cutter 56 having a pair of diametrically opposed V-shaped slots 58 cut in its lower edge.

The leg portion 52 is provided with an opening 60 adjacent its end portion 54 and the edges 62 defining the slots 58 are inwardly beveled, as shown in Figures 6 and 7, so that as the cutter 56 penetrates the upper wall 32 of the container 16, material M will be struck from and folded downwardly into the container without separating from the wall 32 (see Figure 7). Furthermore, the portion 54 will expand the edges defining the opening formed in the wall 32 by the cutter 56 so that the edges will yieldingly grip the leg portion 52 to aid in supporting the container within the body.

Attention is now directed to Figure 8, wherein the air vent means 20a is shown as extending through a downwardly curved recess or passage 18a in the upper wall 12a of the hollow body 10a to communicate the interior of the body with the central recess 34a in the upper wall 12a.

The lower vertical portion P of the vent tube 21a terminates in a tapered portion 26a and a cutter 28a having slots 30a which function similar to the parts 36, 28 and 30 previously described.

One of the outstanding features of the present invention is the spout structure involving an expandable portion 54 which not only assists in gripping the container in place, but also acts as a full and complete seal against leakage of the contents through the perforation without use of a washer or any other such device.

It is noted that the overall height of the case or hollow-body is slightly shorter than a container that is to be received therein, so that as the case, with container inserted, is set on a table, the container will not have the tendency to drop out which would undoubtedly occur if the case were longer than the container.

The vent and spout inserts may be formed in two or more parts which are screwed together.

4

Having described the invention, what is claimed as new is:

1. A pouring attachment for containers comprising a hollow cylindrical body for receiving a container therein, said body having an upper end wall with a recess in its under surface, an arcuate vent tube supported horizontally by said end wall and concealed within said recess, said tube including a depending end portion received in said body and terminating in a pointed extremity having a pair of diametrically opposed V-notches, said extremity adapted to penetrate the upper end of a container placed in the body, means slidably carried by the end wall for ejecting a container from the body, means for retaining a container within the body, and a pouring spout carried by said end wall, said pointed extremity being of a diameter less than said depending end portion and a downwardly extending, inwardly tapered shoulder at the juncture of said pointed extremity with said depending end portion.

2. A pouring attachment for containers comprising a hollow cylindrical body for receiving a container therein, said body having an upper end wall with a recess in its under surface, an arcuate vent tube supported horizontally by said end wall and concealed within said recess, said tube having a depending end portion received in said body terminating in a reduced pointed extremity for penetrating the upper end of a container placed in the body and a downwardly extending, inwardly tapered shoulder joining said depending end portion and said pointed extremity, means slidably carried by the end wall for ejecting a container from the body, means for retaining a container within the body, and a substantially L-shaped pouring spout having a vertical leg portion and an upwardly and outwardly inclined leg portion, said end wall having an upwardly and outwardly inclined opening receiving the inclined leg portion of said spout.

3. The combination of claim 2 wherein the vertical leg portion of said spout is resilient and includes a reduced pointed lower extremity for penetrating the upper end of a container placed within the body and a downwardly extending, inwardly tapered shoulder joining the last-named pointed extremity to said vertical leg portion.

4. A pouring attachment for containers comprising a hollow body, a tubular pouring spout carried by the body and having a vertical portion, said vertical portion including a reduced and sharpened lower extremity for penetrating the upper wall of a container, and a rigid, continuous, downwardly extending inwardly tapered shoulder at the upper end of said lower extremity, said shoulder tapering towards said lower extremity from the vertical portion to cause the upper wall of a container penetrated by said lower extremity to bend downwardly about the vertical portion and with the edges defining the opening formed by said lower extremity yieldingly gripping said vertical portion to retain a container within the body.

5. In a dispenser including a hollow body adapted to receive therein a container, a pouring spout carried by said body and having a tubular and vertical portion, a pair of substantially V-shaped cutters at the lower end of said vertical portion and having their edges inwardly beveled so that the piece of metal punched out by the cutters in the upper wall of a container will remain attached to the upper wall of the container as the container is forced against the cutters, and a rigid, continuous, downwardly extending

shoulder at the juncture of said cutters with said vertical portion, and said shoulder tapering toward said cutters from said vertical portion.

6. A pouring attachment for containers comprising a hollow body adapted to be slipped over a container and including an upper wall having a recess, an arcuate vent tube disposed within the recess and including a depending end portion extending downwardly through said end wall, a downwardly extending inwardly tapered shoulder on said end portion, a cutter extending downwardly from the shoulder and being of a diameter less than the diameter of said end portion, and a pouring spout carried by said end wall.

FRANK MASSARI.
